UNITED STATES PATENT OFFICE.

LAWRENCE RICHARDSON, OF LOUISVILLE, KENTUCKY.

RAILWAY-CAR SIDE BEARING.

Application filed August 6, 1923. Serial No. 655,930.

This invention relates to railway car side bearings.

When moving along a track a car body sways from side to side. The extent of this swaying action depends upon the condition of the track and speed. When a car body sways to one side it comes in contact with the side bearing and is stopped by same. In medium capacity cars it has been found that this blow has a force equal to one half the weight of the car body while in higher capacity cars the force is equivalent to the total weight. Furthermore, it has been found under certain conditions that practically all of the energy of this blow is returned to the car body so that the latter sways over to the opposite side bearing with a blow that is equal to the sum of the blow of the first bearing plus the effect of the irregularities in the track surface. In other words, harmonic action occurs with undesirable results.

Accordingly, one object of the invention is to provide a side bearing which not only has the action of a spring for buffering the blow, but also has a frictional action to prevent the energy of the blow being returned to the car body.

Another object is to provide a simple, novel and efficient side bearing for railway cars adapted to meet the various requirements under service conditions.

These and other objects are accomplished by means of the arrangement disclosed on the accompanying sheet of drawings, in which—

Figure 1 is a fragmentary vertical sectional view of a railway car embodying my invention;

Figure 2 is a detail sectional view of the side bearing showing the spring friction plates unloaded; and

Figure 3 is a similar sectional view of the same side bearing showing the spring frictional plates deflected whereby shocks are yieldably taken and absorbed.

The various novel features of the invention will be apparent from the following description and drawings, and will be particularly pointed out in the appended claims.

The invention is illustrated in connection with a box car having a body 10 including a body bolster 11 with a suitable center bearing contacting with the truck bolster 12 as at 13. As shown in Figures 1 and 2, the body bolster side bearing members 14 are out of engagement with the application

blocks 15 which would be the normal condition under ideal circumstances. However, as mentioned above, due to track irregularities, the car body is caused to sway from side to side, the extent of which depends upon the condition of the track and the speed. Heretofore side bearings have been provided, but such side bearings have been incapable of buffering and absorbing the shocks in a manner to prevent more or less of a serious recoil, resulting in an amplification of the swaying action and excessive shocks of the side bearings occasioned thereby.

To satisfactorily buffer the side bearing blows and to absorb the same in a manner to prevent undesirable recoil, I have provided a side bearing arrangement at each side of the truck including a pile or plurality of superimposed yieldable friction plates 16 which, as shown, are mounted within a side bearing housing 17 carried on the truck bolster 12. When the friction plates 16 are under no load, as shown, for example, in Figures 1 and 2, such friction plates are straight and undeflected. However, when the car body is caused to sway, the body side bearing members 14 on one side or the other pass into engagement with the associated application blocks 15, subjecting the pile of disks or plates 16 to pressure, deflecting same as shown particularly in Figure 3. In this connection it will be noted that the under-surface 18 of each application block 15 is circularly convex and the floor 19 of each bearing housing 17 is circularly concave, so that as the pile of spring plates is subjected to pressure not only do the plates yield in a springlike manner to absorb the shock incident to the swaying, but also said plates have a frictional rubbing action one with respect to the other for dissipating the energy of the blow and preventing an undesirable recoil action, this being especially true in view of the fact that not only do the plates have a frictional rubbing action as the pile is being compressed, but also as the pile is assuming its normal position, as shown in Figure 2.

This side bearing has a high resisting force on a downward or inward movement and an appreciable reduced recoil on the upward or outward movement. By the use of this type of side bearing the swaying action of the car body and accordingly the number of derailments are reduced. There are

lighter blows on the bolsters, side frames, axles and wheel, and wear on the track is reduced.

It is my intention to cover all modifications of the invention falling within the spirit and scope of the following claims.

I claim:

1. In a railroad car, the combination of a truck bolster, a body bolster and a side bearing means interposed between said bolsters, said side bearing means acting as a friction brake and comprising a plurality of superimposed relatively stiff spring plates, in frictional contact on relatively large friction surfaces, said plates being laterally confined and adapted to deflect with frictional resistance under load for absorbing shocks and reducing recoil.
2. In a railroad car, side bearing means adapted to be interposed between the body and the truck bolsters comprising a friction braking device, said friction braking device having a plurality of superimposed relatively stiff spring plates, in frictional contact on relatively large friction surfaces,

said plates being laterally confined and adapted to deflect with frictional resistance under load for absorbing shocks and reducing recoil.

3. In a railroad car, the combination of a car bolster and a truck bolster and side bearing means interposed between said bolsters, said side bearing means comprising a bearing member on one of said bolsters and a cooperating bearing member on the other of said bolsters, said last named bearing member being yieldingly mounted on a friction braking device, said friction braking device comprising a plurality of superimposed relatively stiff spring plates, contacting with relatively large friction surfaces, said plates being laterally confined in a housing having a concaved base, said last named bearing member having a convexed base, whereby under load said friction braking device absorbs shocks imparted through said bearing members and reduces recoil.

Signed at Chicago, Illinois, this 3rd day of August, 1923.

LAWRENCE RICHARDSON.
